(57) **CLAIM**

The ornamental design for a penile prosthesis tubing connector tool, as shown and described.

DESCRIPTION

FIG. 1 is a perspective view of a penile prosthesis tubing connector tool showing a new design:

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top side plan view thereof; and,

FIG. 7 is a bottom side plan view thereof.

The broken lines in the figures form no part of the claimed design.

1 Claim, 7 Drawing Sheets
